Garrison and Loftus
Attorneys.

UNITED STATES PATENT OFFICE.

EUGENE L. HORTON, OF SAN FRANCISCO, CALIFORNIA.

GAME.

Application filed May 31, 1922. Serial No. 564,829.

To all whom it may concern:

Be it known that I, EUGENE L. HORTON, a citizen of the United States, residing at the city and county of San Francisco and State 5 of California, have invented new and useful Improvements in Games, of which the following is a specification.

This invention relates to a game, and particularly pertains to a baseball game.

At the present time there are a number 10 of baseball games on the market which are played upon a board and are provided with various ingenious devices for indicating what plays are to be made and the position 15 of the runners. Most of these games do not agree with the conditions as they arise in a well played baseball game, and it is the principal object of the present invention to provide a baseball game which definitely will cause situations to arise similar to those 20 occurring in a real game, and which make it possible for an exciting game to be played, having a very close and low score.

The present invention contemplates the 25 use of a board, from the surface of which a plurality of projecting pins are arranged in systematic spaced relation to each other, the sides and bottom edges of the board being provided with pockets into which a ball 30 may be lodged when it is released from traps at the top of the board, the pockets each having special significance in the game and designating the play which is to be carried out. For convenience a cover is provided 35 the board, carrying a number of tally markers.

The invention is illustrated by way of example in the accompanying drawings, in which:

40 Fig. 1 is a view in front elevation showing the complete board.

Fig. 2 is a view in end elevation showing a board folded and further disclosing its construction by parts broken away.

45 Referring more particularly to the drawings, 10 indicates a main field over the surface of which pins 11 are arranged in rows, the pins of adjacent rows being staggered relative to each other, and the pins extending 50 perpendicularly from the face of the fields. The sides of the field are bounded by rails 12 and 13, while a cross rail 14 extends across the bottom of the field and connects the lower ends of the side rails. A 55 batting trap 15 is arranged across the top of

the board. This comprises three run-ways 16, 17 and 18, through which a ball 19 may roll onto the field. A top board 20 extends across the run-ways and is formed with openings 21 through which the ball may 60 pass. A slide 22 moves longitudinally of the top board 20 and has a ledge 23 along which the ball may roll to an opening 24. Thus when the opening 24 of the slide is in communication with one of the openings of 65 the board 20 the ball will be permitted to pass through the registering openings to a corresponding passageway, 16, 17 or 18, after which the ball may roll down the field, it being understood that the game board is 70 disposed at a sufficient inclination to insure that the ball will roll. The pins 11 act as obstructions for the ball, it being noted that one pin is placed directly before the exit from each of the passageways 16, 17 and 18. 75 At the opposite ends of the rows of pins are pockets 25 which are formed by upwardly and inwardly inclined ledges 26. As shown in the drawing, these various pockets are utilized to indicate plays to be made. In 80 addition to the obstructing pins 11, four field pockets 26^a are secured to the field and may hold the ball if it falls into the depression of the pocket as indicated at Fig. 2.

It will be observed that the field 10 which is carried on a board forming the back of the game structure provides a box when the side rails 12 and 13 and opposite end closures are considered. This box may be covered by the lid 27 which is preferably 85 hinged to the lower edge of the box and may be swung outwardly as indicated at Fig. 1. The lid carries card plates 28 for receiving the names of the opposing imaginary teams for playing. Between these plates is a 90 pointer 29 pointing to either of the plates, thus indicating which team is "at bat". Arranged in a row below the plates are four pivoted pointers acting in combination with dials by which "runs" and "hits" may be 95 recorded. In the center of the board below this row of dials is a field 30 representing a baseball "diamond" having a home plate, first, second and third bases. Pointers 31 are provided for each of the bases so that 100 it may be indicated which bases are occupied by runners. On opposite sides of the diamond are duplicate dials by which "innings" and "strike outs" are recorded. All of the dials previously described are 105 110

intended to record the continuous performance of both teams for a complete game. In addition three dials, each having pointers, are carried below the diamond field and represent "strikes", "balls", and "outs", respectively. By utilizing all of the dials here shown, it is possible to completely record the performance of both teams for each inning, and also for the entire game, and in addition by the movement of the ball slide 22 there is not liable to be confusion in the number of turns a batter has when "up to bat".

Assuming that an imaginary game is being played between Boston and New York, cards are placed in the frames 28, thus indicating the two teams. The game field is set up at a suitable inclination so that the ball 19 will have no difficulty in rolling across the field until it is lodged at some point thereon. The slide 22 is moved so that its opening 24 is in register with the opening 21 of passageway 16. The ball 19 is then placed on the ledge 23 and allowed to roll to the registering openings, after which it will fall through the openings and roll through the passageway 16 onto the field. It will then pursue a random course between and across the various pins and pockets. When the ball comes to rest in a pocket the play is made as indicated by the pocket in which the ball was lodged. This play is then carried out or otherwise recorded on the recording dials and field carried by the lid of the box. The ball slide 22 is then moved to bring the opening 24 in registry with the second opening 21 of the board 20, after which the ball is allowed to roll along the ledge 23 to the opening 24 and onto the field previously described. The indicated play is then recorded and the ball slide again removed to the third hole 21 of the board 20. When the ball has been played successively through the holes until three players are out, one team is considered to have had its turn and the other team will take its turn to complete the inning. The game then progresses as previously described.

It will thus be seen that with the game board here disclosed, a complete game may be played having all of the excitement of a real game, and providing that plays will be brought about without possibility of manipulation by the players, and that these plays may be readily recorded without confusion.

While I have shown the preferred form of my invention as now known to me, it will be understood that various changes might be made in the combination, construction and arrangement of parts by those skilled in the art, without departing from the spirit of the invention as claimed.

Having thus described my invention,

what I claim and desire to secure by Letters Patent is:

1. A baseball game comprising a board having spaced upstanding elements each provided with a pocket in one side, said board also having a plurality of spaced pins and a plurality of pockets along the side and bottom edges thereof, and a runway at one end of the board above the base of the board and provided with perforations through which an object may drop onto the board and roll against and between said upstanding elements and said pins and enter a pocket according to its direction of travel through and between said elements and pins. 70 75 80

2. A baseball game comprising a board having upstanding elements each provided with a pocket in one side, said board also having a plurality of pockets along the side and bottom edges thereof and a plurality of spaced pins projecting upwardly from the board so that a ball may pass over the board between said upstanding elements and said pins and enter a pocket according to its direction of travel through and between said elements and pins, a runway above the base of the board having perforations therein through which a ball may pass onto the board and roll against and between said upstanding elements, and said pins, and enter a pocket according to its path of movement between the elements and pins, and means for selecting which of the perforations the ball will pass through. 90 95 100

3. A baseball game comprising a board having upstanding elements each provided with a pocket in one side, said board also having a plurality of pockets along the side and bottom edges thereof and a plurality of spaced pins projecting upwardly from the board so that a ball may pass over the board between said upstanding elements and said pins and enter a pocket according to its direction of travel through and between said elements and pins, a runway above the base of the board having perforations therein through which a ball may pass onto the board and roll against and between said upstanding elements, and said pins, and enter a pocket according to its path of movement between the elements and pins, and a perforated member slidably over said runway and the perforations thereof and provided with a perforation adapted to register with the perforations of said runway interchangeably to permit of passage of the ball selectively through the perforations of the runway. 105 110 115 120

4. A baseball game comprising a board having a plurality of elements projecting upwardly therefrom, and also having a plurality of pockets formed thereon, a runway above the base of the board having perforations through which a ball may drop onto 125 130

the board and roll from under said runway along the board and roll against and between said upstanding elements and enter one of the pockets.

5. A baseball game comprising a board having spaced elements projecting upwardly therefrom and also having a plurality of pockets formed therein, and a runway above the base of the board at one end thereof and having perforations through which a ball may drop onto the board and roll from under said runway along the board and roll against and between said elements and enter a pocket.

15. 6. A baseball game comprising a board having spaced elements projecting upwardly therefrom and also having a plurality of pockets formed therein, and a runway above the base of the board at one end thereof and having perforations through which a ball may pass onto the board and roll against and between said elements and enter a pocket, and a member slidable over the

perforations of the runway and provided with a perforation for registration interchangeably with the perforations of the runway whereby to select the perforation through which the ball may pass.

25. 7. A baseball game comprising a board having spaced elements projecting upwardly therefrom and also having a plurality of pockets formed therein, and a runway above the base of the board at one end thereof and having perforations through which a ball may pass onto the board and roll 30 against and between said elements and enter a pocket, and a member slidable over the perforations of the runway and provided with a perforation for registration interchangeably with the perforations of the 35 runway whereby to select the perforations through which the ball may pass, and means whereby to record the play designated by the balls which lodge in the pockets.

EUGENE L. HORTON.
